CLAIM

I claim the ornamental design for a clamping device, as shown and described.

DESCRIPTION

FIG. 1 is a front perspective view of the clamping device. FIG. 2 is a front view thereof, the rear view being a mirror image.

FIG. 3 is a right side elevation view thereof.

FIG. 4 is a left side elevation view thereof.

FIG. 5 is a top plan view thereof; and,

FIG. 6 is a bottom view thereof.

The broken lines shown are for illustration purposes only and form no part of the claimed design.
